US00D944840S

(12) **United States Design Patent** (10) **Patent No.:** **US D944,840 S**
Goette et al. (45) **Date of Patent:** **** Mar. 1, 2022**

(54) **DISPLAY SCREEN OR PORTION THEREOF
WITH GRAPHICAL USER INTERFACE**

(71) Applicant: **Brainlab AG**, Munich (DE)

(72) Inventors: **Hubert Goette**, Munich (DE); **Martin Leidel**, Munich (DE); **Annika Mueller**, Munich (DE); **Michaela Ecker**, Munich (DE); **Antonia Henning**, Munich (DE)

(73) Assignee: **BRAINLAB AG**, Munich (DE)

(**) Term: **15 Years**

(21) Appl. No.: **29/753,748**

(22) Filed: **Oct. 1, 2020**

Related U.S. Application Data

(62) Division of application No. 29/673,015, filed on Dec. 11, 2018, now Pat. No. Des. 916,782.
